UNITED STATES PATENT OFFICE.

FIDELIS JOHNSON, OF DELPHOS, OHIO.

COMBINED FURNACE AND FLUE-WELDER.

1,346,753.

Specification of Letters Patent. Patented July 13, 1920.

Application filed April 16, 1919. Serial No. 290,483.

To all whom it may concern:

Be it known that I, FIDELIS JOHNSON, a citizen of the United States, residing at Delphos, in the county of Allen and State of

5 Ohio, have invented certain new and useful Improvements in Combined Furnaces and Flue-Welders, of which the following is a specification.

This invention relates to a combined furnace and flue welder.

One object of my invention is to provide a device of this character in which the mandrel is stationary and does not whirl the flue during the process of welding and also 15 in which the welding roller rotates around the flue and mandrel during such process.

A further object of my invention is to provide for the use of mandrels of different sizes whereby flues of different diameters 20 may be welded.

A still further object of my invention is to provide for the engagement of the flue with the mandrel by passing it through and without removing it from the heating furnace.

With the foregoing and other objects in view that will appear as the nature of the invention is better understood, the same consists in the novel features of construction, 30 combination and arrangement of parts illustrated in the drawings and more particularly pointed out in the appended claim.

In the accompanying drawings, in which like parts are designated by like characters 35 throughout the several views:—

Figure 1 is a plan view of a combined furnace and flue welder, embodying my improvements.

Fig. 2 is a side elevation thereof.

40 Fig. 3 is a similar view, with parts shown in section.

Fig. 4 is a detail sectional view of the roller, its bearing head and associated parts, all shown on an enlarged scale.

45 Fig. 5 is a detail face view of the sleeve used in coupling the lever arm of the welding roller to the hollow actuating shaft, the latter shown in transverse section and Fig. 6 is a detail perspective view.

50 Referring to the drawings for a more particular description of the invention and which drawings are for illustrative purposes only and are therefore not drawn to scale, the numeral 1 represents the supporting frame, 2 the furnace, 3 a downwardly inclined box or receptacle for the fuel, 4 the

blower, 5 the blower pipe leading to and communicating with the air chamber 6 beneath the furnace, 7 the stationary mandrel and 8 the welding roller.

60

The mandrel is removably secured to the inner or front end of the shaft 9 by one or more set screws 10 or other equivalent means. The shaft 9 is held stationary or against rotation by the bracket 11, secured at one end, 65 as at 12, to the frame 1, with its upper free end extending through a corresponding opening 13 in the adjacent end of said shaft.

A hollow cylindrical drive sleeve 14 is rev- 70 olubly mounted upon the stationary shaft 9 and extends from the rear end of the mandrel to the outer end of said shaft, said sleeve being journaled in the bearings 15 and 16 mounted on top of the supporting frame 1.

The sleeve 14 is driven by a belt 17 pass- 75 ing over a pulley 18 keyed to the outer end of the sleeve and over a second smaller pulley 19 keyed to the countershaft 20, journaled in suitable bearings, as 21, of the sup-

porting frame. The shaft 20 is provided 80 with a fast and loose pulley 22 and 23, re- spectively, and is driven by a belt (not shown) leading to a gasoline engine, motor, or other source of power. The belt used in driving the shaft 20 is shifted from the 85 fast to the loose pulley, or vice versa, by the belt shifter 24. The blower is driven by the belt 25 which passes over a relatively large pulley 26 on the shaft 20 and over a second smaller pulley 27 carried by the blower 90 shaft 28.

The welding roller 8, which is preferably 95 of solid cylindrical form, is journaled between the outwardly projecting ears or lugs 29 of the bearing head 30, which is adjust- ably secured by the bolt and nut 31 and 32, respectively, or other equivalent means, to the longitudinally slotted, outwardly and right-angularly bent portion 33 of the lever arm 34, which is disposed in a horizontal 100 position. The outer end of the right-angu- larly bent portion of said lever arm termi- nates in an outwardly bent extension 35 and working through said extension and engag- ing the bearing head 30, is a set screw 36, 105 which may be locked in adjusted position by the lock nut 37 and prevents outward dis- placement of the welding roller 8 during the welding process. The lever arm 34 is ful- crumed intermediate its ends, as at 38, be- 110 tween any one pair of the outwardly and radially projecting extensions or ribs 39

formed on the outer surface of the hollow cylindrical coupling sleeve 40, which is keyed to and rotates with the drive sleeve 14. The lever arm 34 is formed with an inwardly curved outer end 41 adapted to be engaged by a cone 42 slidably mounted on the sleeve 14 and adapted to be moved in one direction by the foot treadle 43, pivoted, as at 44, to the frame 1 and provided at the upper end of its vertical portion, with a yoke 46, which has a slot and stud connection, as 47, with said cone.

My machine is used in the welding of boiler tubes or flues and for the sake of explanation, it will be stated that in removing boiler flues from the boiler to be cleaned, it is necessary to cut off the ends of the flues, and hence, in order to replace the same flues, they must be lengthened by welding a short piece of tubing, usually five or six inches in length, on each flue.

In practice, the flue with the section or piece of tubing as 48, to be welded thereon, is placed in the furnace by inserting through the opening 49 in the front wall thereof, until the outer end of said section or piece abuts against or engages the abutting plate 50, carried by the upright arm 51 of the rock shaft 52, journaled to the supporting frame 53 above the discharge end of the blower pipe 5. A horizontally disposed hand lever 54 is connected to one end of said rock shaft and is held in horizontal position by the latch 55. After the flue with the piece or section of tubing to be welded thereon has been heated in the furnace to the required temperature, the hand lever 54 is raised to lower or shift the abutting plate into a horizontal out-of-the-way position, as indicated in Fig. 3. The flue, together with the piece or section of tubing to be welded thereon, is then passed through the opening 56 in the back wall of the furnace and passed over and adjusted on the mandrel 8, also as shown in Fig. 3. The drive sleeve 14 having been previously set in motion by applying the power, the welding roller 8 will be swung outwardly away from the mandrel by centrifugal force, leaving sufficient space between the roller and mandrel for the adjusting of the flue on the latter, as previously described. The flue, with the piece or section of tubing to be welded thereon having been passed over the mandrel, the cone 42 is slid or moved forwardly on the drive sleeve 14 by depressing the foot treadle 43 against the action of the coil springs 57, the tendency of which are to hold the cone in retracted or inoperative position. This operation throws the roller 8 in, which rotates around the mandrel and works over the flue at the joint at the pressure required. During the welding process,

the rotating action of the roller 8, will cause the flue to gradually turn approximately three-quarters of a revolution around the mandrel, which gives the operator a clear vision of the weld around the flue joint, that is, at the point of connection of the piece of tubing with the flue.

The discharge end of the blower pipe is provided with a damper 58, actuated by the hand lever 59, whereby the temperature of the heat generated by the furnace may be regulated by the operator to meet the requirements, as is apparent, or the air blast from the blower entirely shut off.

In using my furnace there will be no fire glare to injure the eyes or any great heat to which the operator will be exposed, as in the ordinary flue welding fires. The furnace is preferably lined with common fire brick and can be relined when required.

Different sized mandrels may be used for different size flues, ranging from 1 and $\frac{1}{4}$ to 4 inches in diameter.

From the foregoing description taken in connection with the drawings, it is thought that the construction, operation and advantages of my invention will be readily understood without requiring a more extended explanation.

Various changes in the form, proportions and minor details of construction may be resorted to without departing from the principles or sacrificing any of the advantages of this invention as defined in the appended claim.

Having described my invention, what I claim as new and desire to secure by Letters Patent, is:—

In a machine of the character specified, a supporting frame, a hollow cylindrical drive sleeve journaled thereon, a stationary shaft extending through and beyond one end of the drive sleeve, a stationary mandrel, removably secured to the projecting end of said shaft, a coupling member keyed to the inner end of the drive sleeve and rotating therewith, a roller mounted to revolve around the mandrel and over the end of a flue to be welded, a horizontally disposed lever arm fulcrumed to the coupling member, said lever arm carrying said roller, and means under the control of the operator for swinging the roller in against the end of a flue to be welded, said means comprising a cone mounted for end-wise movement on the drive sleeve, resilient means normally holding the cone in retracted or inoperative position and a foot treadle for shifting the cone forwardly under the adjacent end of the lever arm against the action of said resilient means.

In testimony whereof I affix my signature.

FIDELIS JOHNSON.
